CLAIM

The ornamental design for a submersible vessel and/or replicas thereof, as shown and described.

DESCRIPTION

FIG. 1 is a front-top-left perspective view of a submersible vessel and/or replicas thereof showing my new design;

FIG. 2 is a rear-top-left perspective view thereof;

FIG. 3 is a rear-top-right perspective view thereof;

FIG. 4 is a front elevational view thereof;

FIG. 5 is a rear elevational view thereof;

FIG. 6 is a top plan view thereof;

FIG. 7 is a bottom view thereof; and,

FIG. 8 is a left-side elevational view thereof, the right-side elevational view being a mirror image thereof.

1 Claim, 8 Drawing Sheets
